BOBBIN SELECTOR FOR WEFT REPLENISHING LOOMS

Carl P. Bergstrom, Worcester, Mass., assignor to
Crompton & Knowles Loom Works, Worcester,
Mass., a corporation of Massachusetts

Application January 2, 1943, Serial No. 471,108

6 Claims. (Cl. 139—232)

This invention relates to improvements in weft replenishing looms and it is the general object of the invention to provide improved mechanism for permitting the replenishment of single shuttles from plural groups of reserve bobbins in a rocking or movable magazine.

A type of weft replenishing loom which has gone into use for the manufacture of fine fabrics employs a rocking magazine having two stacks of reserve bobbins which are utilized for replenishing two shuttles. The position of the magazine with respect to the transfer mechanism is determined by a control exercised by the shifting shuttle box mechanism so that one stack replenishes one shuttle and the other stack replenishes the other shuttle. When a single shuttle is used in such looms it is desirable that the full capacity of the magazine be available for replenishment of the shuttle. It is an important object of my present invention to provide a loom wherein a rocking magazine can be shifted from one position to another position in a given rotation so that all the stacks of bobbins may be utilized.

The loom referred to operates with a normally stationary lever which is given a working stroke on replenishing beats of the loom and the lever is associated with positioning mechanism which will rock the magazine if reserve bobbins are to be drawn from one stack but will permit the magazine to remain unchanged if the reserve bobbins are to be taken from the other stack. This result is accomplished by a positioner hook or the like operatively connected to the magazine and movable into and out of the path of an actuator on the lever. The hook is placed by a controller lever and it is a further object of my invention to operate the controller lever preferably by connections to the setting lever to cause the hook to occupy alternate positions for successive replenishing operations of the loom. In this way the stacks are depleted uniformly for the replenishment of a single shuttle and the full capacity of the magazine utilized.

With these and other objects in view which will appear as the description proceeds, my invention resides in the combination and arrangement of parts hereinafter described and set forth.

In the accompanying drawings, wherein a convenient embodiment of my invention is set forth,

Fig. 1 is a side elevation of a loom having my invention applied thereto,

Fig. 2 is a detail vertical section on line 2—2 of Fig. 1,

Fig. 3 is a side elevation looking in the direction of arrow 3, Fig. 2.

Figs. 4 and 5 are diagrammatic views showing the selector mechanism and the operating connections therefor in two different positions, and

Fig. 6 is a detail plan in the direction of arrow 6, Fig. 1, on an enlarged scale.

Referring particularly to Fig. 1, I have shown a loom frame 10 having lay L which is reciprocated in usual manner by connectors 11 actuated by the top shaft 12 of the loom. The lay is provided with a shuttle box B to receive a shuttle S which is picked back and forth across the loom in usual manner. In the present instance shuttle S is the only one which is used in the loom, or at least the only one which is replenished. The lay carries a bunter 13 which normally passes above a transerrer latch 14 pivotally mounted at 15 on a transerrer arm 16. A stud 17 affords pivotal support for the transerrer arm and is carried by a magazine frame 18 fixed with respect to the loom frame.

The magazine M in the present instance is provided with front and back stacks R and R', respectively, of similar reserve bobbins. The bobbins of these stacks gravitate toward low position and the lowest bobbins are held in transfer position by yielding supports designated generally at 20. The supports are located at the bottoms of their respective stacks of bobbins and tend to hold the adjacent bobbins so that the latter can move alternately to transfer position as the magazine rocks. A stud 21 is carried by the frame 18 and affords pivotal support for the magazine M so that the latter can rock either to place the lowest bobbin of stack R or the lowest bobbin in stack R' in transfer position under the transerrer arm 16.

A rod 25 is connected at 26 to the magazine frame and has the rear end thereof attached to an arm 27 secured to a rocking shaft 28. The latter is supported by a bracket 29 on a loom frame and has secured thereto a second arm 30 which is attached to the upper end of a magazine positioner rod 31. The lower end of rod 31 has adjustably connected thereto a positioner hook 32 for downward actuation. A spring 33 normally holds the magazine in the position shown in Fig. 1 with the lowest bobbin of front stack R under the transerrer arm 16.

The loom is provided with a weft detector D preferably of the electrical type and as shown in Fig. 1 is electrically connected to a solenoid

35. On alternate picks of the loom when shuttle

S occupies box B and the lay moves forwardly the detector will determine the condition of weft in the shuttle and when the latter is depleted of weft the solenoid 35 will be energized to lift its core 36 to operate mechanism described herein-after.

A relatively large stud 40 is fastened to the lower part of the loom frame and has mounted thereon a regularly rocking lever 41 which carries a roll 42 located in the groove 43 of a cam 44 on the loom bottom shaft 45. This shaft is geared by mechanism not shown to the top shaft in such a manner that the bottom shaft makes one rotation for two rotations of the top shaft. A dog 46 is pivoted to the forward end of lever 41, the left end as viewed in Fig. 1, and normally rises along a path at one side of a shelf 47 which is fixed with respect to a normally stationary or setting lever 48. The latter is also pivoted on the stud 40 and has the rear arm 49 thereof provided with a stud 50 for actuation of the hook 32. A controller lever 55 for the positioner hook 32 is pivoted at 56 on a stationary support 57 secured to the stud 40.

The forward end of setting lever 48 is connected to vertical rod 60 the upper end of which is pivoted to a rocking head 61 pivoted at 62 on a fixed support. The head is provided with a latch lifter 63 and a shuttle position detecting feeler 64. A spring 65 normally holds the forward end of the setting lever down so that the latch lifter 63 permits the transfer latch 14 to remain in low position and the shuttle feeler 64 in its front position where it will not be engaged by the shuttle.

In the matter thus far described, the lay L reciprocates once for each beat of the loom and dog 46 rises every second beat preferably while the shuttle is on that side of the loom opposite the magazine. When the detector D calls a replenishing operation the dog 46 will be deflected from its normal position under the shelf 47 by a trip 67 controlled by the cradle 37 due to actuation of the solenoid 35. As the front end of lever 41 rises under these conditions the rod 60 will be elevated, the lifter 63 will raise the latch 14 into the path of the bunter 13, and the shuttle feeler 64 will be moved rearwardly to its shuttle feeling position. The loom is thus set for a replenishing operation. At the same time that rod 60 is raised the stud 50 descends on a working stroke either to lower the positioner hook 32 if the controller lever 55 is in forward position, that is, to the left as viewed in Fig. 1, or leave the hook 32 unmoved if the controller 55 is in rear position. Rocking of the magazine M about its pivot 21 from one position to the other position thereof is therefore seen to depend upon whether the positioner hook 32 is in or out of the path of the descending stud 50 as the loom is set for a transfer operation. As previously used the controller lever 55 has been connected to shifting shuttle boxes but in the present instance the boxes are omitted and other means are provided to move lever 55.

Except as indicated hereinafter the matter thus far described is of common construction and for a further understanding of the structure and operation thereof reference may be had to Patents Nos. 2,054,173, 2,054,192, 2,128,974, and 2,262,308.

In carrying my present invention into effect, I provide means for rocking the magazine so that bobbins for successive transfer operations are drawn alternately from the stacks R or R' to enable the full capacity of the magazine to be used for replenishment of the shuttle. The previously

described support 57 has a foot 70 which is preferably bolted at 71 to the floor under the loom for the purpose of holding the support 57 firmly in stationary position. The controller lever 55 has rotatably mounted thereon a roll 72 under the pivot 56 for engagement with a cam 73 which has three equiangularly spaced high dwells 74 and three intervening low dwells 75. These high and low dwells are effective to move the controller lever 55 from one extreme position to the other extreme position thereof as the cam makes a $\frac{1}{6}$ rotation.

The cam is rigid with respect to a ratchet wheel 78 having six teeth 79 for cooperation with a pawl 80 pivoted at 81 to a feed lever 82. The latter is pivoted on a stud 83 carried by a stand 84 fastened to the floor. A yielding lock arm 85 also pivoted on stud 83 is connected to a spring 86 the effect of which is to move the arm 85 against a yielding lock wheel 87 turning with and rigid with respect to the cam and ratchet wheel. A spring 88 between stand 84 and lever 55 holds roll 72 against the cam 73 and tends to move lever 55 rearwardly. A stud 90 carried by the support 84 affords pivotal support for the cam, the ratchet and the lock wheel.

The feed lever 82 is connected to an upwardly extending rod 91 pivoted at 92 to the rear arm 49 of the setting lever. The location of stud 90 with respect to stud 40 and the amplitude of movement of the setting lever 48 are such that a full movement of the setting lever will move the pawl 80 through a sufficient distance to give the ratchet 78 a $\frac{1}{6}$ turn.

In the operation of my invention it may be assumed that the magazine is in the position shown in Fig. 1 with the lowest bobbin in stack R in transfer position under the transerrer arm 16 and that roll 72 is on a low dwell 75 of the cam so that the upper part of the controller 55 is held in its rear position by spring 88 with positioner hook 32 out of the path of the stud 50. The magazine will be held yieldingly in the normal position shown in Fig. 1 by spring 33 until caused to rock by stud 50. When a replenishing operation occurs under the assumed conditions the setting lever 48 will be rocked in a clockwise direction as viewed in Fig. 1 to raise rod 60 to set the loom for transfer and also move the stud 50 downwardly at one side of the hook 32, thus permitting the magazine to remain in normal position. At the same time the actuator rod 91 is depressed so that the pawl 80 moves on its idle stroke from high to low position where it can engage the next tooth of the ratchet wheel. After the shuttle has been replenished by a bobbin from stack R the setting lever 48 will move in a counterclockwise direction as viewed in Fig. 1 due to the action of spring 65 and the shape of the cam which controls the motion of the dog 46. This return motion of the setting lever occurs after the lay has moved rearwardly an appreciable distance behind its front center position and after the transerrer arm has been restored to its normally raised position. During the return motion of the setting lever rod 91 will be raised and pawl 85 will have a working stroke to turn the ratchet wheel 78 one-sixth of a rotation and move a high dwell 74 under roll 72. Controller lever 55 is thus moved forwardly to shift the positioner hook 32 to the left as viewed in Fig. 1 into the path of the stud 50.

When the next replenishing operation of the loom occurs the stud 50 when descending will engage the hook 32 and lower rod 31 to rock the magazine from its normal position shown in

Fig. 4 to that shown in Fig. 5 to place the bottom bobbin of reserve stack R' in transfer position under the transerrer hammer 16. The stud will hold the magazine in the position shown in Fig. 5 from some time prior to the start of transfer until arm 16 has returned to raised position. During this second transfer the shuttle will be replenished by a bobbin derived from the rear stack R' and when the parts are restored to their normal position after transfer as already described in connection with the first transfer, the pawl 80 will be given another working stroke to rock the cam $\frac{1}{6}$ of a rotation and place another low dwell 75 under roll 72. The controller 55 is therefore returned to the position it occupied for the first transfer and on the third transfer the stud 50 will miss the hook 32 and permit the magazine to remain in the position shown in Figs. 1 and 4 so that the shuttle will be replenished for the second time by a bobbin derived from the front stack R.

As succeeding transfers occur the cam 73 is moved with a step by step movement and the controller 55 rocks first backwardly and then forwardly to place the hook 32 in the path of the stud 50 for alternate transfer operations of the loom and out of said path of the stud for the intervening operations. In this way the bobbins are drawn alternately from the two stacks R and R' for the replenishment of the shuttle S and the full capacity of the magazine can be utilized for renewing the weft in the shuttle.

In order that the relation between the finger 67 and the dog 40 may be adapted to the condition set forth in the foregoing description I prefer as shown in Fig. 6 to hold the cradle 37 in stationary position so that it does not shift with the controller lever 55. As shown in that figure the solenoid core 36 is connected to a trip 100 pivoted on a rod 101 carried by a frame 102 mounted on lever 48. The finger 67 is one of two similar fingers which are used on the type of loom set forth herein and employed for weaving fabrics having two different wefts.

In the present instance, however, the weft is all the same and there is no need for shifting the cradle 37, therefore I employ pins 103 in the guide rod 104 of frame 102 so placed as to prevent shifting movement of the cradle 37 along rod 104. In this way one finger 67 is positioned for operation by the trip 100 whenever a replenishing operation is initiated by the weft detector, and this finger deflects the lifting dog under the shelf on setting lever 48. While I prefer to use the pins 103 for the purpose described, I find that they are not always necessary and if desired the cradle 37 can be connected to the controller lever 55 by a rod 105 which will have the effect of shifting the cradle, as usual when the loom operates with two shuttles, so that one or another of the indicator fingers 67 will be operatively related with respect to the trip 100. This latter procedure, however, requires unnecessary movement of parts which can remain stationary and it is for this latter reason that I prefer to use the pins 103.

It will be obvious from the foregoing description that the forward end of the setting lever 48 rises before transfer starts and remains raised until after the transerrer arm 16 has returned to its normal raised position. Movement of the setting lever therefore occurs before and after the interval assigned to the replenishing opera-

tion and cradle 37 could if desired slide simultaneously with shifting of the controller lever 55. Furthermore, although I have shown the return stroke of the setting lever as providing the working stroke of the pawl 80, I do not wish necessarily thus to be limited, since the movements of the setting lever occur either before or after the transferring interval and either of such movements can be utilized to turn the cam 10 73 for locating the controller lever 55 in sufficient time to permit stud 50 to rock the magazine before a transferring operation starts.

From the foregoing it will be seen that I have provided a simple form of control for the controller 55 the effect of which is to move the positioner hook 32 into and out of the path of the actuating stud 50 to permit replenishment of the shuttle first from one stack and then from the other stack of reserve bobbins in the magazine. The rocking of the magazine to its two operating positions is effected by control mechanism for the controller 55 which derives its actuating force from the setting lever 48. It is to be understood that the magazine tends normally to assume the position shown in Fig. 1 by action of spring 33 and after it has been rocked to the position of Fig. 5 incident to depression of the hook 32 by stud 50 to permit replenishment of the shuttle from the rear stack R' of bobbins, the magazine will return to the position of Fig. 1 as the stud 50 rises. I am not limited in the practice of my invention to the exact structure described, inasmuch as it is sufficient if the magazine can occupy two different positions during transferring operations and the control for those positions is such that bobbins are drawn alternately from stacks R and R' for successive operations of the loom. The magazine can normally place the rear stack of bobbins in replenishing position, if desired, as shown in Patent No. 2,128,974 without departing from the spirit of my invention.

Having thus described my invention it will be seen that changes and modifications may be made therein by those skilled in the art without departing from the spirit and scope of the invention and I do not wish to be limited to the details herein disclosed, but what I claim is:

1. In a weft replenishing loom operating with a shuttle to be replenished by bobbins drawn from a plurality of stacks of reserve bobbins in a magazine which rocks to place the stacks one at a time in replenishing position, weft replenishing mechanism to move a bobbin from the stack in replenishing position into the shuttle upon depletion of weft in the latter, an actuator having a movement whenever the weft replenishing mechanism operates, a positioner for the magazine operated by said actuator, and a controller for the positioner operated by the actuator and effective to cause the positioner to effect movements of the magazine so that the stacks move to replenishing position one at a time and in a given sequence during a succession of replenishing operations of the loom.

2. In a weft replenishing loom operating with a shuttle and having a pair of stacks of reserve bobbins in a movable magazine which is normally positioned to locate one of said stacks in replenishing position and the other stack out of replenishing position, mechanism to replenish the shuttle when depleted with a bobbin from whichever stack is in replenishing position, an actuator having a working stroke on every replenishing operation of the loom, a positioner

for the magazine movable into the path of the actuator and thereupon caused by the latter to move the magazine to place said other stack in replenishing position, the magazine remaining in normal position when the positioner is out of the path of the actuator, a controller for the positioner, means operated by the actuator to give the controller a step by step movement, one step for each replenishing operation of the loom, and connections between the controller and the positioner to cause the latter to be out of the path of said actuator on alternate replenishing operations of the loom and in said path of the actuator on the intervening replenishing operation of the loom to cause said stacks to be in replenishing position alternately for successive replenishing operations of the loom.

3. In a weft replenishing loom operating with a shuttle and having a pair of stacks of reserve bobbins in a movable magazine which is normally positioned to locate one of said stacks in replenishing position and the other stack out of replenishing position, mechanism to replenish the shuttle when depleted with a bobbin from whichever stack is in replenishing position, an actuator having a working stroke for each replenishing operation of the loom, a cam having high and low dwells, means operated by the actuator to give the cam step by step movements, a positioner for the magazine, and connections between the cam and the positioner effective to move said positioner into the path of the actuator for alternate replenishing operations of the loom, said positioner when in the path of the actuator being moved by the latter on a working stroke thereof to move the magazine to place said other stack in replenishing position.

4. In a weft replenishing loom operating with a shuttle and having a pair of stacks of reserve bobbins in a movable magazine which is normally positioned to locate one of said stacks in replenishing position and the other stack out of replenishing position, a normally stationary lever, means to lock said lever preparatory to a replenishing operation of the loom, weft replenishing mechanism set for operation by the lever when the latter rocks to effect movement of a bobbin from whichever stack is in replenishing position into the shuttle, a positioner for the magazine, and a controller for the positioner operated by said lever and effective to cause alternate operations of the lever to actuate said positioner and cause the latter to move the magazine from normal position to place said other stack in replenishing position.

5. In a weft replenishing loom operating with a shuttle to be replenished by bobbins drawn from a pair of stacks of reserve bobbins in a magazine which can rock to place either stack in replenishing position and is normally positioned to locate one of said stacks in replenishing position, weft replenishing mechanism to transfer a bobbin from the stack which is in replenishing position into the shuttle when the latter is depleted of weft, an actuator having a movement for each replenishing operation of the loom, a hook operatively connected to the magazine and movable into and out of the path of the actuator and effective when in said path and moved by said actuator on a working stroke thereof to shift the magazine to cause the other of said stacks to move to replenishing position, a cam having high and low dwells, a cam lever positioned by said cam and operatively connected to said hook, a pawl and ratchet mechanism operatively connected to the cam and operated by the actuator whenever the latter has an operating stroke, said pawl and ratchet mechanism effective during successive movements thereof to cause the high and low dwells of the cam alternately to position the cam lever to effect movement of the hook into the path of the actuator for alternate operations of the latter.

6. In a weft replenishing loom operating with a shuttle to be replenished by bobbins drawn from a pair of stacks of reserve bobbins in a magazine which can rock to place either stack in replenishing position and is normally positioned to locate one of said stacks in replenishing position, weft replenishing mechanism to transfer a bobbin from the stack which is in replenishing position into the shuttle when the latter is depleted of weft, an actuator having an operating stroke for each replenishing operation of the loom, a hook operatively connected to the magazine, a positioner for the hook shiftable to move the hook into and out of the path of the actuator, a control lever for the positioner, a cam having high and low dwells to engage the lever and move the same to effect movement of the positioner for the purpose of moving the hook into and out of the path of the actuator, and feed mechanism for the cam effective to cause the cam to move the lever for each operation of the actuator and thereby cause the hook to move into the path of the actuator on alternate working strokes thereof and effect movement of the hook out of the path of the actuator on the intervening strokes thereof.

CARL P. BERGSTROM.
